UNITED STATES PATENT OFFICE.

CHARLES F. BAKER, OF BOSTON, MASSACHUSETTS.

SHANK-STIFFENER.

SPECIFICATION forming part of Letters Patent No. 362,923, dated May 17, 1887.

Application filed March 9, 1887. Serial No. 230,193. (No model.)

To all whom it may concern:

Be it known that I, CHARLES F. BAKER, of Boston, county of Suffolk, and State of Massachusetts, have invented an Improvement in 5 Shank-Stiffeners, of which the following description, in connection with the accompanying drawings, is a specification, like letters on the drawings representing like parts.

This invention relates to stiffeners for the shanks of boots or shoes, and has for its object to provide a wire stiffener of serpentine form, which in practice may be fastened at both ends, the deflections of the stiffener extending across the shank in the direction of 15 its width.

Prior to my invention I am aware that wire has been used to replace the usual flat steel shank, the said wire being bent to form three parallel arms extended longitudinally in the 20 shank. Such a spring possesses many advantages over the ordinary flat steel shank-stiffener; but in practice it has been found that, among other things, the said open-end wire spring shank-stiffener does not prevent the 25 boot or shoe to which it is applied from twisting.

I have ascertained by experiment that a shank-stiffener composed of spring-wire may be made to possess all the advantages of the 30 open-end wire spring shank-stiffener, and the additional advantage not possessed by the same—namely, that of preventing the boot or shoe from twisting—provided the deflections of the wire extend crosswise of the shank; and 35 as the result of my experiments I have produced a novel shank-stiffener composed of a wire serpentine in form for a part or the whole of the length of the wire, as will be described.

My invention therefore consists, essentially, 40 of a shank-stiffener composed of a wire bent into serpentine form, the deflections of the wire extending across the shank.

Figure 1 is a longitudinal vertical section of a shoe having my improved serpentine spring-wire stiffener applied thereto; Fig. 2, a view 45 of the stiffener removed from the shoe, and Fig. 3 a modified form of stiffener.

Referring to Fig. 1, A represents a boot or shoe having applied between its inner sole, a, and its outer sole, a', my improved serpentine spring-wire stiffener b, it having one end fastened near the ball and the other at the heel of the shoe by nails b', or other suitable fastening device.

55 The serpentine spring-wire shank-stiffener

is formed of a single piece of wire of sufficient size and strength to restore the boot or shoe to its normal or original shape whenever the pressure, which acts to distort or force the boot or shoe from its original shape, is removed.

The single piece of wire from which my improved shank-stiffener is made may be twisted or made serpentine throughout its length, as shown in Fig. 2; or it may be twisted or made 60 serpentine for a portion of its length, as in Fig. 3, the deflections of the wire extending across the shank, preferably obliquely to the length of the said shank, the wire on either side of the serpentine portion, as shown in Fig. 70 75 3, being straight, except at the ends, where it is bent to form an eye, b¹, for the reception of the nail or other fastening device. The wire being bent at its ends, as shown, prevents the said ends from cutting into the leather or other stock.

My improved serpentine-wire shank-stiffener possesses all the advantages of the open-end wire shank-stiffener—such as the driving of pegs or nails in tapping or resoling, and in 80 pegging on the shank-filling—and, in addition, it possesses sufficient stiffness and strength, by virtue of its serpentine form, to prevent the boot or shoe from twisting, and thus spoiling its shape.

Furthermore, the serpentine form of stiffener enables the stiffener to be rigidly fastened at both ends, the said twisted or curved portions of the stiffener being compressed together, after the manner of a spiral spring, 90 when abnormal pressure is exerted upon it.

I have herein shown my improved shank-stiffener as fastened at the ends; but, if desired, it may be fastened at the center or at any other portion of its length.

I claim—

The herein described spring-wire shank-stiffener, composed of a single wire bent or twisted into serpentine form for some portion of its length, the deflections extending in the 100 direction of the width of the shank, to operate as and for the purpose set forth.

In testimony whereof I have signed my name to this specification in the presence of two subscribing witnesses.

CHARLES F. BAKER.
